(57) **CLAIM**

The ornamental designs for a multi-functional adaptor, as shown and described.

DESCRIPTION

FIG. 1 is a first perspective view of a multi-functional adaptor;

FIG. 2 is a second perspective view of the multi-functional adaptor;

FIG. 3 is a front view the multi-functional adaptor;

FIG. 4 is rear view the multi-functional adaptor;

FIG. 5 is a left side view the multi-functional adaptor;

FIG. 6 is a right side view the multi-functional adaptor;

FIG. 7 is a top view the multi-functional adaptor;

FIG. 8 is a bottom view the multi-functional adaptor; and,

FIG. 9 is a use state reference view of the multi-functional adaptor.

The broken lines depict portions of the multi-functional adaptor that form no part of the claimed design.
